UNITED STATES PATENT OFFICE.

RICHARD SCHAPLER, OF FRANKFORT-ON-THE-MAIN, GERMANY.

FIRE-ESCAPE LADDER.

SPECIFICATION forming part of Letters Patent No. 723,925, dated March 31, 1903.

Application filed December 11, 1901. Serial No. 85,502. (No model.)

To all whom it may concern:

Be it known that I, RICHARD SCHAPLER, a subject of the Emperor of Germany, and a resident of Frankfort-on-the-Main, in the 5 Kingdom of Prussia, Germany, have invented certain new and useful Improvements in Fire-Escape Ladders, of which the following is a full, clear, and exact specification.

This invention relates more particularly to 10 that class of fire-escape ladders such as shown and described in my United States Letters Patent No. 610,692, issued September 13, 1898, having self-contained means whereby the ladder may be extended to the desired elevation 15 through the agency of compressed gas or fluid; and the invention has for its primary object to provide improved and simple means for relieving the shock or concussion heretofore resulting from the sudden stopping of 20 the relatively movable members when they reach the limit of their maximum movement.

With these ends in view my invention consists in certain features of novelty in the construction, combination, and arrangement of 25 parts by which the said objects and certain other objects hereinafter appearing are attained, all as fully described with reference to the accompanying drawings and more particularly pointed out in the claims.

30 In the said drawings, Figure 1 is a vertical longitudinal sectional view of two of the telescope-sections of an extensible fire-escape ladder provided with my improvements, the section being taken on the line 1 1, Fig. 2. Fig. 35 2 is a similar section taken on the line 2 2, Fig. 1. Fig. 3 is a transverse section taken on the line 3 3, Fig. 1; and Fig. 4 is a section similar to Fig. 1, showing the inner section or member elevated to the limit of its 40 stroke.

1 2 represent telescoped pipe-sections provided with ladder-sections 3 4, respectively, connected thereto in any suitable way, as described and shown in my aforesaid patent, to 45 which reference may be had for an understanding of the parts of this apparatus shown in said patent, my present invention concerning itself more especially with means for deadening the shock or concussion of the telescopic sections when they arrive at the limit 50 of their upward movement. In the accompanying drawings I have shown but two of

these sections; but it will nevertheless be understood that their number may be multiplied as desired. The outer section 2 is considerably larger in diameter than the inner section 1, and its upper end is contracted around the latter section, as shown at 5, to form a close fit and prevent the escape of the air under pressure utilized for raising the inner section, and the inner section is of course closed at its upper end or at some other point to prevent the escape of the air or pressure fluid through it, thus constituting of the inner section a piston or plunger. The lower end of 60 the inner section is provided with a cushioning device adapted to abut against a ring or flange 6, secured within the outer section at a slight distance from the upper extremity thereof, and this cushioning device comprises 70 a plurality of elastic rings 7, composed of india-rubber or other suitable material and arranged one upon the other within the pipe-section 1, each ring, if desired, being provided in its under side with an annular air-chamber 8, which adds to the elasticity. These rings are so placed one upon the other that when all are compressed the air-chamber of each upper ring will be closed by the upper surface of the ring immediately below 80 it, and the air-chamber of the bottom ring will be closed by a cap 9, secured to the lower end of inner pipe-section 1 in any suitable way, as by means of a threaded flange 10, screwed on the end of the pipe. This cap 9 85 also constitutes a support for the ring and for receiving the impact thereof when the inner pipe-section reaches the limit of its upward stroke.

Threaded or otherwise secured in the center of the cap 9 is a stem 11, which is preferably hollow and which passes upwardly through all of the rings, and sleeved on the upper end of this stem is a washer 12, which fits accurately within pipe-section 1 and rests 95 upon the top ring, and this washer is the means by which the impact is imparted directly to the upper ring, and it receives an impact from a cross-bar 13, which extends across the washer and projects through vertically-elongated slots 14 in the pipe-section 1 and also through side slots 15 in the hollow stem 11, the outer extremities of the cross-bar 13 being arranged in line with the flange 100.

6, so as to strike thereagainst when the inner pipe-section is elevated, and thus cause the shock to be absorbed by the elastic rings.

While I have described my invention with 5 reference to a ladder, it will nevertheless be understood that it is equally applicable to other uses, such as for elevating water-towers, raising hose-pipe, &c.

Having thus described my invention, what 10 I claim as new therein, and desire to secure by Letters Patent, is—

1. In a fire-escape ladder, the combination of a plurality of telescoped sections, a cushion device secured to the inner section, an 15 abutment within the outer section adapted to receive the impact of the inner section and a rigid member supported by said cushion device and adapted to engage said abutment, substantially as set forth.

2. In a fire-escape ladder, the combination of a plurality of telescoped sections, an elastic medium carried on the inner end of the inner section, a cross-bar resting upon said elastic medium and projecting from the side 25 of said inner section, and an abutment in the outer section for receiving the impact of said cross-bar, substantially as set forth.

3. In a fire-escape ladder, the combination of a plurality of telescopic sections, an elastic 30 medium supported within the inner section, a cross-bar projecting through said inner section and supported upon said elastic medium, and an abutment in said outer section for receiving the impact of said cross-bar, substantially as set forth.

4. In a fire-escape ladder, the combination of a plurality of telescopic sections, the inner one of which is provided with longitudinal side slots, an elastic medium arranged within 40 said inner section and supported thereby, a cross-bar resting upon said elastic medium and projecting through said side slots, and an abutment within the outer section adapted to receive the impact of said cross-bar, substantially as set forth.

5. In a fire-escape ladder, the combination of a plurality of telescopic sections, a plurality of elastic members arranged within the inner

one of said sections and having air chambers or grooves in their faces, each closed by contact with the contiguous elastic member, and means for imparting the impact of said inner section to the outer section through intermediary of said elastic members, substantially as set forth.

6. In a fire-escape ladder, the combination of a plurality of telescopic sections, a plurality of elastic rings arranged within the inner section and having grooves in their faces closed by contact with one another, a washer resting upon said rings, a cross-bar projecting through said inner section and resting upon said washer, and an abutment within the outer section for receiving the impact of said cross-bar, substantially as set forth.

7. In a fire-escape ladder, the combination of a plurality of telescopic sections, the inner one of which is provided with side slots, an elastic medium arranged within the inner section, a cap secured on the end of the inner section for supporting said medium, a washer resting upon said medium, a cross-bar resting on said washer and protruding through said side slots, and an abutment in said other section for receiving the impact of said cross-bar, substantially as set forth.

8. In a fire-escape ladder, the combination of a plurality of telescopic sections, the inner one of which is provided with side slots, a plurality of elastic grooved rings arranged within said inner section, a cap secured on the end of said inner section and supporting said rings, a stem secured to said cap and projecting through said rings and having side slots arranged in line with the aforesaid side slots, 85 a washer resting upon said rings around said stem, a cross-bar resting upon said washer and passing through the side slots in said inner section and stem, and an abutment in said outer section for receiving the impact of said cross-bar, substantially as set forth.

RICHARD SCHAPLER.
